UNITED STATES PATENT OFFICE.

STRICKLAND L. KNEASS, OF PHILADELPHIA, PENNSYLVANIA, ASSIGNOR TO WILLIAM SELLERS & COMPANY, INCORPORATED, OF PHILADELPHIA, PENNSYLVANIA, A CORPORATION OF PENNSYLVANIA.

PROCESS OF CONTINUOUSLY SUPPLYING STEAM AT LOW PRESSURE TO INJECTORS.

Original application filed August 5, 1924, Serial No. 730,293. Divided and this application filed July 1, 1925. Serial No. 40,817.

My invention relates to a method whereby steam at low pressure is supplied to pre-heat and give an initial velocity to the feed water in injectors and is, for example, 5 adaptable for use in connection with injectors on locomotives where economy of steam is of primary importance.

The object of my invention is to provide a method whereby steam at substantially 10 constant pressure may be supplied to the low pressure part of an injector, for example on a locomotive, from the exhaust of a working cylinder and whereby live steam will be automatically admitted to the injector supply pipe and expanded therein to 15 meet the requirements of the low pressure part of the injector when steam is cut off the working cylinder, whereby the injector may be continuously operated whether the 20 locomotive be standing, drifting or working.

Having now indicated, in a general way, the nature and purpose of my invention, I will proceed to a detailed description of an apparatus with which the method embodying 25 my invention may be practically carried out, with reference to the accompanying drawings, in which—

Fig. 1 is a side elevation of a locomotive showing the application of my invention.

Fig. 2 is a sectional view of automatically 30 operated live and exhaust steam valves.

Fig. 3 is an end view, partly broken away, of the subject of Fig. 2.

Fig. 4 is a sectional view of a detail of 35 my invention.

a indicates the boiler, *b* one of the cylinders, and *c* the steam chest of a locomotive. *d* indicates the injector for supplying water to the boiler and having the 40 low pressure part *d'*, while *e* represents a manually controlled main injector operating valve for supplying live steam to the injector.

Exhaust steam from the cylinder passes 45 through the conduit *f*, and the low pressure steam supply to the injector is through pipe *g*; the conduit *f* and the pipe *g* being, respectively, connected to the body *h* in which is a winged piston valve *i* adapted to 50 control the passage of exhaust steam to the injector.

A pipe *j* connects the live steam valve *e*

with the body, the admission of live steam to pipe *g* being controlled by a valve *k*.

The valves *i* and *k* are opened or closed 55 by steam chest pressure and are so arranged that when the locomotive is working the valve *i* will permit the passage of exhaust steam to the injector, while when the locomotive is idle, as standing or drifting, the 60 valve *i* will be automatically closed and the valve *k* automatically opened to permit the passage to the injector of live steam, expended to reduce its pressure. The construction of the mechanism for automatically 65 operating the exhaust and live steam admission valves will be clear from the following description.

On the upper part of the body *h* and in axial alignment with the valve *i* is a cylinder 70 *l*, which is connected to the steam chest through a branch *m* and pipe *n*. Within the branch *m* is a piston *o* resting on a plunger *p*, in turn resting on an outer piston *q* and connected by a major spring *r* 75 with an inner piston *s* provided with a stem *t* which is connected with the valve *i*. An inner spring *u* surrounds the stem *t* and abuts against a thimble *v* and the lower end of the cylinder. Communication between 80 the exhaust conduit *f* and the inner piston *s* is constantly permitted through the aperture *w* in the cylinder and aperture *w'* in thimble *v*. Clearance is provided between piston *q* and the upper part of cylinder *l* 85 to permit communication between the upper part of the cylinder and atmosphere through threaded aperture 15 to insure atmospheric pressure on the top of the piston *q*.

In operation, when steam is admitted to 90 the steam chest, by opening the throttle of the locomotive, live steam pressure is exerted on the piston *o*, which is forced down to the limit of its stroke and forces down the plunger *p* and outer piston *q*, which acting 95 through the major spring *r*, causes the inner piston *s* and its stem *t* attached to the valve *i* to be moved downward, thus opening the valve and permitting exhaust steam to pass to the injector through pipe *g* and at the 100 same time compressing spring *u*. Exhaust steam from the conduit *f* passing through the apertures *w w'* exerts a pressure beneath the inner piston *s*, and, when the exhaust

pressure rises, lifts the piston, its stem and the attached valve *i* against the action of the major spring *r*, which abuts against the plunger *p*, which, under the steam chest pressure on piston *o*, acts as a fixed abutment. The valve *i* is thus more or less closed by rise in exhaust pressure to be again returned to normal by the major spring with decrease in exhaust pressure, in order that the valve may act to automatically maintain a substantially constant pressure in the pipe *g*.

In the ordinary locomotive, or any reciprocating type of prime mover, both the inflow and outflow from the cylinders is intermittent. The discharge, therefore, from the cylinder exhaust pipe is in periodic waves of high and low pressure, proportional to the impulse and frequency. Such variation in pressure is disturbing to the action of an injector, and I have devised means to break the waves of pressure and induce a more even flow of exhaust steam to the regulating valve and injector, through the conduit *f* to valve *i*, and thence through the pipe *g* to the injector. In order to flatten out such waves and reduce the necessity for throttling through the medium of inner piston *s*, there is set in the conduit *f* a body *h* of greater diameter than the conduit and divided into inner and outer chambers by means of a cylindrical screen section *13*, transversely of which is a baffle plate *14*, the central portion of which is concaved, as shown in Fig. 4. Exhaust steam from the cylinder at varying pressures enters the cylindrical screen direct from conduit *f*, strikes the baffle and is deflected laterally through the meshes of the screen. The steam then passes around the baffle and returns through the meshes of the screen into conduit *f* and thence to valve *i*. The effect of striking the baffle *14* is to eliminate a large part of the momentum of the peak of the wave of exhaust steam; the finely perforated cylindrical screen *13* breaks into small jets the flow into the surrounding chamber, and this action is repeated when the steam passes through the other portion of the perforated screen into the conduit connected with the regulating valve. This eliminates the remaining impulses and gives a practically even and continuous discharge toward the injector.

If steam be cut off from the steam chest, as when the locomotive is stopped or allowed to drift, the pressure is removed from piston *o* and piston valve *i* will be closed by the action of spring *u*, which acts to lift the various parts into the position shown in Fig. 2.

On the upper part of the body *h* and adjacent to the cylinder *l* is a cylinder *x*, in axial alignment with the valve *k*, and connected through a branch *y* and pipe *n* with

the steam chest. Within the cylinder *x* is a piston *z* which seats upon a port *2*, between the lower portion of the cylinder and a chamber *3*, which is connected to the main injector operating valve *e* by means of pipe *j*. Port *2* is also closed by an upwardly seating valve *4*, provided with a cylindrical guide *5* having an aperture *6* for the passage of steam. The valve *4* is connected by means of a stem *7* to the outlet valve *k*, which controls a port affording communication between chamber *3* and an orifice *8* leading to the body *h* in such a manner that when one is open the other is closed. The orifice *8* may be varied by adjustment of screw *9*, which permits the size of the orifice to be such as to allow for the passage of only as much live steam as when expanded in body *h*, will produce the pressure desired to the low pressure part of the injector. Suitable outlet space *10* and a conduit *11* leading to the exhaust pipe are provided to prevent accumulation of balancing pressure under the piston *z* or on top of valve *4*.

When pressure is on the steam chest, that is, when the cylinder is working, the valve *i*, as above described, is opened as a result of pressure on piston *o*. At the same time, steam chest pressure is on piston *z* and live steam pressure is present in chamber *3* and above valve *4* and acts to retain the valve *4* and outlet valve *k* in respectively open and closed position as shown in Fig. 2.

If now steam is shut off from the steam chest, pressure is relieved from the top of piston *z* and the piston is lifted by the pressure above valve *4*, arising from the passage of steam from chamber *3* through aperture *6* in guide *5*. When piston *z* is lifted, the pressure above valve *4* is dissipated to the exhaust pipe through the outlet space *10* and conduit *11*. With pressure relieved from the top of valve *4*, the pressure in chamber *3* acting beneath the valve lifts and closes it at the same time the valve *k* is lifted off its seat through its connection with valve *4*, and live steam is permitted to pass to and through orifice *8* into body *h*, where it expands and passes to the injector through pipe *g* at desired pressure.

If now the locomotive be started up, steam chest pressure is again exerted on pistons *o* and *z*, the former seating on the base of its cylinder and the latter on port *2* closing the port from the live steam chamber *3*. The pressure on piston *o* effects the opening of valve *i*, as above described. Pressure on piston *z* causes the piston to move down and, before it seats, to stroke the upper end of stem *7* and move the steam, valve *4* and outlet valve *k* downward. This action is due to pressure on the larger area of the piston *z* compared to the valve *4* even though the pressure in the steam chest is somewhat below that in chamber *3*.

After the preliminary downward movement of valve 4, steam from chamber 3, when the injector operating valve E is opened, passes through aperture 6 and equalizes the pressure on the top and under side of valve 4, so that the pressure of the steam closes the outlet valve *k* cutting off live steam from the pipe *g*, which is then receiving exhaust steam as a result of the opening of valve *i*.

10. Thus, it will be noted that with the main injector operating valve *e* open the low pressure part of the injector is continuously supplied with steam either from the exhaust, when the locomotive is working, or from the 15 boiler when the locomotive is standing or drifting, and further that the continuous supply of steam is maintained automatically.

It will be appreciated that the apparatus above described, and which forms the subject-matter of an application filed by me 20 August 5, 1924, Serial No. 730,293, issued November 24, 1925, as Patent No. 1,563,196, of which this application is a division, is 25 illustrative of satisfactory apparatus for carrying out my invention, but my invention is not to be limited to the use of any particular apparatus.

Having now fully described my invention, what I claim and desire to protect by Letters 30 Patent is:

1. In the operation of an injector having a high and low pressure element, supplying steam at low pressure to the low pressure element of the injector from the exhaust 35 of a steam engine when it is working and from a steam generator when the engine is not working and regulating automatically the pressure of the steam supplied to the low pressure element of the injector from 40 either the steam generator or exhaust to obtain a substantially constant pressure within the low pressure element irrespective of the higher pressure obtaining in the steam generator or of variation in exhaust 45 pressure.

2. In the operation of an injector having a high and low pressure element, supplying steam at low pressure to the low pressure element of the injector from the exhaust of 50 a steam engine when it is working and from a steam generator when the engine is not working and regulating under the influence of exhaust pressure the pressure of the steam supplied to the low pressure element 55 of the injector from either the steam generator or exhaust to obtain a substantially

constant pressure within the low pressure element irrespective of the higher pressure obtaining in the steam generator and of variation in exhaust pressure.

3. In the operation of an injector having a high pressure element and a low pressure element, supplying steam at high pressure to the high pressure element, controlling the supply of steam at high pressure, supplying steam at low pressure to the low pressure element of the injector from the exhaust of a steam engine when it is working and from the 60 steam generator when the engine is not working and regulating the pressure of the steam supplied to the low pressure element of the injector from either the steam generator or exhaust to obtain a substantially constant pressure within the low pressure element independently of the control of the 65 supply of steam at high pressure and irrespective of the higher pressure obtaining in the steam generator or of variation in exhaust pressure.

4. In the operation of an injector having a high and low pressure element, supplying steam at low pressure to the low pressure element of the injector from the exhaust of a steam engine while it is working and so regulating the flow of exhaust steam to the 70 low pressure element with relation to exhaust steam available as to maintain a substantially constant pressure within the low pressure element irrespective of variation of exhaust pressure.

5. In the operation of an injector having a high and low pressure element, supplying steam at low pressure to the low pressure element of the injector from the exhaust of a steam engine while it is working and from a steam generator when the engine is not working and so regulating the flow of steam to the low pressure element from either the generator or exhaust with relation to the pressure obtaining in the generator or to 75 exhaust steam available as to maintain a continuous supply of steam to the low pressure element at a substantially constant pressure irrespective of the higher pressure obtaining in the generator or of variation of 80 exhaust pressure.

In testimony of which invention, I have hereunto set my hand, at Philadelphia, Pennsylvania, on this 27th day of June, 1925.

STRICKLAND L. KNEASS.
